SINGLE CRYSTAL X-RAY TUBE TARGET
Michael J. Zunick, Hubertus, Wis., assignor to General
Electric Company, a corporation of New York
Filed Apr. 30, 1962, Ser. No. 191,688
1 Claim. (Cl. 313—330)

This invention relates to X-ray tubes, and particularly, to the use of targets constituting a single crystal of metal in such tubes. The invention is broadly applicable to X-ray tubes used for diagnostic and therapeutic purposes as well as for tubes employed in X-ray emission or diffraction studies.

An X-ray tube used for any of the above purposes includes an envelope that supports in its evacuated interior a cathode structure spaced from an anode. The cathode has a hot filament that emits electrons which are accelerated to the anode in a focused beam that produces X-rays at the point or line of impact on a target insert in the anode. Initially, the target surface is polished so that the emitted X-rays on any line of sight appear to emanate from a sharp line or point, depending upon how the electron beam is focused. When the target insert is in this condition a uniformly intense X-ray beam is emitted in any specified direction. Thus, if the tube is used for taking radiographs, sharp images, without penumbra, are produced because all rays appear to emanate from a single point. If the tube is of the line focus type commonly used to make X-ray diffraction studies of crystalline materials, better resolution of the rays diffracted by the sample results.

Users of X-ray tubes for both radiographic and analytical purposes have demanded increased electron beam current ratings in order to obtain more intense X-ray output and at the same time they have demanded smaller and sharper focal spots. An effect of increasing the beam current and at the same time concentrating it is to overheat or even melt the target surface. The resultant roughening constitutes permanent damage to the target for it is no longer possible to obtain a sharp focal region thereafter. Hence, commercial X-ray tubes are designed to compromise desired rating with a reasonable life.

In radiographic X-ray tubes tungsten is the material most commonly used for targets. Tubes used for emission and diffraction work may employ targets of tungsten, molybdenum, vanadium, tantalum, chromium, nickel, copper, cobalt or iron. Although these metals are considered pure, they are characterized by a polycrystalline structure having minute grain boundaries that are separated by oxides and other impurities. The grains are sometimes completely enveloped in impurities. This results in a weak atomic bond between crystallites and makes the target material more susceptible to the type of thermal deterioration mentioned above.

Metallurgical studies, particularly photomicrographs, taken on a section of the target material cut through the focal spot in prior art tubes reveals that a number of permanent changes may take place when a tube is used. The crystallites often recrystallize into larger sizes and these may also break down into smaller sizes under thermal stress and the resulting migration and reformation causes subsurface voids and pronounced surface irregularities to develop. The small discrete crystallites or grains are even more vulnerable to dislocation by the impinging electron beam. In extreme cases, pieces of the target material in the region of the focal spot are known to have broken off and deposited in undesirable places within the X-ray tube envelope.

Surface irregularities in the region of the focal spot are especially harmful in tubes used for X-ray diffraction studies. In these tubes the X-ray beam is taken off at an angle of about one to five degrees with respect to the plane

2

of the target. It is evident that any disruptions, depressions or protuberances on the surface of the target will drastically affect X-ray output at these low angles because some parts of the beam will be shaded or cut off. These irregularities also disperse the X-rays at undesired angles so that, in addition to the intensity being reduced, resolution is seriously impaired.

A fundamental object of the present invention is the provision of a new X-ray tube target that facilitates producing a sharp focal region and higher X-ray output intensities from an X-ray tube without diminishing its useful life.

Other specific objects are to overcome the above noted problems of target deterioration and poor thermal conductivity through the use of a target material a single crystal of pure substance having preferred thermal and other physical properties.

Achievement of the foregoing and other more specific objects will appear from time to time throughout the course of the specification which follows.

Single crystals have produced some surprising results when they are used for X-ray tube target inserts. Because they contain only trace amounts of impurities, they are ideal for X-ray diffraction tubes where the spectral purity of the characteristic radiation emitted from the target is of great consequence. Because of their mono crystalline structure they have no grain boundaries. This yields multiple advantages such as a thermal conductivity 50% greater than that of the polycrystalline metals, and an electrical resistivity of about 80% of the usual polycrystalline sintered and cold worked target materials. These latter properties are partly the result of the single crystals having a density which is immeasurably different than the 100% theoretical density of the pure metals. The new single crystal targets are non porous and have only minor gas occlusions so that outgassing is more certain and requires less time.

The absence of grain boundaries in the single crystal targets has virtually eliminated target deterioration in the form of roughening, cracking, delamination, recrystallization, X-ray scattering and disintegration or fragmentation that was heretofore manifested when a previously overloaded X-ray target was subjected to further heavy electron bombardment. A prior art diffraction tube that was operated at 50 kilovolts-peak, 20 milliamperes continuous duty and had a nominal focal spot size of 0.8 x 15.0 millimeters could reasonably be expected to have a useful life of about 600 hours. A tube using the new single crystal target, which was in all other respects, similar to the prior art tube, was operated with the same focal spot size at twice the current, or 40 milliamperes, for almost twice as many hours as could be expected from the previous tubes, without any perceptible deterioration of the target surface. The sharpness of the beam and the purity of X-ray output remained.

Photomicrographs of the new tube targets showed no surface erosion of any consequence nor was there any subsurface metallurgical alteration. Even though there were a few minor cracks due to thermal stresses along the cleavage planes, they were across the focal spot and so did not interfere significantly with the conduction of heat to the sides or from the focal spot to the back of the target.

A more detailed description of the invention, its use and advantages will now be set forth in connection with the following drawing in which:

FIG. 1 shows an exemplary X-ray tube, partly in section, in which the new single crystal target material is employed;

FIG. 2 is a plan view of the X-ray tube anode and target assembly taken on the section lines 2—2 in FIG. 1;

FIG. 3 is a single crystal target insert such as may be used in the anode shown in FIG. 2.

Refer now to FIG. 1 where the invention is illustrated in an X-ray tube that is primarily designed for X-ray diffraction analysis. The illustrative tube 10 comprises an evacuated glass envelope 11 joined to a mounting flange 12 through the agency of a ferrule 13. The ferrule may be Kovar metal brazed annularly on flange 12 and in metal to glass sealing relation with envelope 11. Flange 12 also has brazed to it a cylindrical metal anode extension 14 which is closed at one end by an anode 15 of any suitable metal such as copper. Anode 15 has a centrally located rectangular target insert 16 from whose interiorly exposed surface X-rays are generated. It will be observed that target insert 16, anode 15, extension 14 and flange 12 are all electrically connected and at the same potential. Since the tube 10 is mounted on X-ray apparatus on flange 12 these parts, and the apparatus, are usually at ground potential.

X-rays emitted from a line or spot source on the surface of target insert 16 radiate in all directions but a useful beam passes exteriorly of the tube through an X-ray transmission window symbolically shown as item 17. Windows 17 are usually beryllium a few mils thick so as to minimize X-ray attenuation. In diffraction tubes, up to four windows are commonly employed.

Envelope 11 is provided with a central re-entrant portion 18 that terminates in a press 19 which is joined to a cathode assembly 20 through a conventional glass to metal seal in the region of 21. On the end of cathode 20, adjacent target insert 16, there is a concavity 22 constituting a focusing cup of a character well known in the X-ray tube art. Insulatingly supported within focusing cup 22 is an elongated helical filament 23 that is substantially coextensive with the long dimension of target insert 16. Conductors 24 supply current for heating filament 23 to a temperature where it emits electrons that may be accelerated to target insert 16. Since the target is at ground potential, filament 23 is made very negative with respect to it. In X-ray tubes used for emission and diffraction analysis, the potential difference between anode and cathode is usually 75 kilovolts or under but in diagnostic and therapeutic tubes this voltage is usually appreciably higher.

Tubes of this type commonly have their anode 15 water cooled but this feature has been omitted because it is well known in the art. An exemplary water cooled X-ray tube may be seen in U.S. Patent No. 2,846,753, issued to M. J. Zunick et al. August 12, 1958, and is assigned to the instant assignee.

An example of how the tube is used is also depicted in FIG. 1 where there is shown a crystalline sample 25 undergoing X-ray diffraction analysis. The front surface of sample 25 makes a low angle α with respect to the plane surface of target 16. Thus, even though the width of the focal spot were equal to the width of target insert 16, the beam of X-rays 26 impinging on sample 25 would have a thin, elongated cross section or a line focus as it is ordinarily termed. The sharpness of this focus affects the sharpness or resolution of the reflected or refracted beam 27 which may be directed to an X-ray detector through collimating slits, neither of which is shown. A more complete X-ray optical system in which tube 10 may be employed may be seen in Klug and Alexander, X-Ray Diffraction Procedures, John Wiley & Sons, New York, 1954, page 241.

The new single crystal metal target insert 16 may be vacuum cast into the anode 15 by conventional techniques that are described in more detail in the above cited Zunick et al. Patent No. 2,846,573. For present purposes it is sufficient if one appreciates that target 16 is embedded in good heat exchange relationship with anode 15.

The single crystal target insert 16 may have dimensions essentially the same as polycrystalline targets used heretofore although it is desirable to minimize the new crystal dimensions for economic reasons. As an illustration, in one tube design, a $\frac{3}{8} \times \frac{3}{4} \times \frac{1}{16}$ inches tungsten insert is

used. This is embedded in a copper base to enhance heat transfer.

Where single crystals of metals such as tungsten, molybdenum, vanadium, niobium and tantalum are used for target inserts it is desirable to have the (110) atomic lattice plane parallel with the target surface because these and some other metals that one may want to use have a body centered cubic crystal structure that is most dense in this plane. Where other metals are used, other planes of maximum density may be preferred and specified by those knowledgeable in the metallurgical art. Single crystals whose lattice planes are identified with respect to the crystal faces, and in some cases, crystals whose lattice planes are specified by the customer may be obtained from the Linde Company division of Union Carbide Corporation, Chicago, Illinois, and other suppliers.

The single crystal target insert should be as smooth as possible on its X-ray emitting surface. By conventional shop methods crystals with satisfactory surface smoothness were obtained by surface grinding to a finish which was not irregular in excess of 125 microinches. The surface was then electrolytically etched by conventional techniques to assure that there was no cold worked metal present in the surface. This can be readily checked before assembly in an X-ray tube anode with an X-ray diffractometer such as one schematized at the cited page and other locations in Klug and Alexander's book that was previously mentioned. In the diffractometer the intensity and sharpness of the X-rays diffracted by the single crystal sample serves as an indication of spectral purity and smoothness. A photomicrograph of a target surface treated in the foregoing manner will reveal a homogeneous surface, without the presence of grains, grain boundaries or impurities. Thus, there is practically no tendency for the single crystal to recrystallize or undergo grain boundary separation or to roughen when subjected to a concentrated, high energy electron beam.

In certain cases, especially in X-ray tubes that are used for diffraction or emission analysis, it is desired to produce a spectrum of radiation with peak intensities at predetermined wavelengths. In such cases an alloyed target may be desirable but they are not known to have been used in the past because, when made by prior art sintering and forming techniques, they had low thermal conductivity and were more disposed to deteriorate in the manner mentioned earlier. This problem may be overcome by using single crystal alloys. For example, dependent upon the X-radiation spectrum desired, one may elect to use crystals of hafnium boride, titanium nitride or tantalum carbide. Other combinations may become available in the future.

The new single crystal X-ray targets have been described primarily in connection with an X-ray tube that has a stationary anode but it will be appreciated by those versed in the art that single crystals may also be used in targets for rotating anode tubes as well. As an example, a large cylindrical single crystal may be cut into wafers that are rotated about their axes while the electron beam impinges on their faces. Various other ways of using the single crystals in rotating anode tubes will appear to those versed in the art.

In summary, there has been described a new X-ray target material in the form of single crystals of compositions appropriate to the X-ray spectrum desired. The new targets result in X-ray tubes with higher ratings and longer life. They are especially useful for X-ray analysis techniques because of their capability for preserving a smooth target surface and spectral purity under rated and reasonable overload conditions.

Because a preferred use of the invention has been described, many other applications will now appear to those skilled in the art. It should, therefore, be understood that such description is illustrative rather than limiting and that the scope of the invention should be determined only by construing the claim which follows.

I claim:

An X-ray tube comprising:

- (a) a gas-tight envelope,
- (b) a source of a focused electron beam sealed in the envelope,
- (c) an anode structure,
- (d) a target element that consists of a single crystal of metal which is fixed in the anode structure and which has one surface that is impinged by the electron beam 10 to produce X-rays,
- (e) an X-ray permeable window in the envelope for

5

6

transmitting a beam of X-rays from the one surface to the outside of the envelope,
(f) the said single crystal target element having a body centered cubic atomic lattice structure, and
(g) the (110) lattice plane of said crystal being in substantial parallelism with the said one surface.
